APPARATUS FOR WORKING RAILWAY POINTS AND SIGNALS
BY MEANS OF ELECTRICAL ENERGY
Filed Sept. 24, 1930

INVENTOR:
D. G. Downes,

BY *A. R. Vencill*

His ATTORNEY.

UNITED STATES PATENT OFFICE

DAVID GORDON DOWNES, OF LONDON, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

APPARATUS FOR WORKING RAILWAY POINTS AND SIGNALS BY MEANS OF ELECTRICAL ENERGY

Application filed September 24, 1930, Serial No. 484,102, and in Great Britain September 30, 1929.

This invention relates to apparatus for working railway points or signals wherein the movement is effected by means of an electro-motor through suitable gearing.

It is well known in connection with the electrical operation of points and signals that when the source of electrical energy is limited in voltage, such as, for instance when derived from a primary battery, a relatively long period is required by the electro-motor to complete the movement of the points and signals in order that the current output may be reduced to such proportions as to be readily maintained by the battery. In the case of point operation especially, this slow motion introduces an element of danger arising from the fact that should a train inadvertently approach the points while being moved, the train would be derailed. It is desirable, therefore, that the actual movements of the points should be made as quickly as possible so as to allow as short a time as possible during which the points may be in an unsafe condition. Likewise, the movement of a signal should be made as quickly as possible in order that a deliberate and unmistakable indication may be given to a driver.

According to the invention, the energy provided by the battery through its electro-motor is stored up in a spring or weight, which in turn is electrically released to move the points or signals quickly at the appropriate time.

In order that the invention may be clearly understood it will now be described with reference to the single figure of the accompanying drawing which is a diagrammatic view showing the general arrangement of an operating mechanism embodying the invention.

Referring now to the drawing the points are arranged to be actuated by a point operating slide 1 adapted to be coupled by mechanism hereinafter described to a sliding member 2 mounted in suitable guides (not shown). The slide 2 is surrounded by a helical spring 3 interposed between abutments 4, 5 at opposite ends thereof. Also engaging with the ends of the spring 3 are projections 7, 8 carried by a sliding frame 9 the end portion 10

of which is internally screw threaded so as operatively to engage with a rotatable screw threaded shaft 11. The shaft 11 is connected by any suitable gearing such for instance as a bevel gear 12 to an electric motor 13 supplied with operating current from a battery 14.

The motor circuit includes a switch device 15 of any suitable construction adapted to complete the circuit of the motor 13 so long as the sliding frame 9 occupies the position shown in the drawing and until this frame has been moved to the right so as to compress the spring 3 to a predetermined extent. As here shown, the switch device comprises two bridging members 15^a and 15^b operatively connected to frame 9 and coacting with pairs of bars 15^c and 15^d respectively.

The slide 2 is provided with slots or recesses 16, 17 adapted to be engaged by a locking bolt 18 operated by an electromagnet 6 so as to maintain the slide 2 stationary during the compression of the spring 3. The slide 2 is also provided with a recess or aperture 19 adapted to register with a corresponding aperture 20 in the point operating slide 1.

The apertures 19, 20 are adapted to accommodate a sliding bolt 21 actuated by an electromagnet 22 carried by the slide 1 in such a manner that when the electromagnet 22 is energized the bolt 21 is raised so as to project through both apertures 19 and 20 and thereby couple the point operating slide 1 to the slide 2.

The bolt 21 is provided with a projection or extension 23 the lower end of which is adapted to enter one or the other of two recesses 24, 25 formed in a stationary locking element 26.

The projection 23 is also provided with a contact 27 adapted when the bolt 21 is in its raised position to engage with fixed contacts 28 included in the circuit of the electromagnet 6, the latter of which derives current from the battery 30.

The circuit for the electromagnet 22 includes a battery 31 and a normally open contact 32 controlled by a point operating lever, so that when this contact is closed the electromagnet is energized.

In order to ensure the rotation of the motor 13 in the desired direction to compress the spring 3 in readiness for the desired movement of the points the motor circuit includes a reversing switch device 29 operated by the point operating slide 1.

The operation of the apparatus is as follows:

With the parts of the mechanism in the position shown in the drawing, current flows from battery 14 through the reversing switch device 29, wire 33, contact 15^c—15^a—15^c of switch device 15, motor 13, and wire 34 to battery 14. This causes the motor 13 to rotate in a direction effecting the corresponding rotation of the screw threaded rod 11 to cause the sliding frame 9 gradually to move towards the right.

As a result the arm 7 of the frame 9 engages the left-hand end of the spring 3 and effects the gradual compression of the spring, the opposite end of this spring being held stationary by its engagement with the projection 5 on the slide 2 which is held fixed during this action by the locking bolt 18, which engages with the recess 16 in the normal deenergized condition of the electromagnet 6. As soon as the spring 3 has been compressed by the movement of the frame 9 to a predetermined extent the bridging members 15^a will leave the contact bars 15^c and this will open the circuit of the motor 13 with the result that current is no longer supplied to the motor which accordingly ceases to operate.

The mechanism is now in a condition for operating the points this being effected in the following manner:

The signalman by operating the point lever 40 closes the energizing circuit of the electromagnet 22 at contact 32, with the result that the locking bolt 21 and its projection 23 are raised so as to cause the bolt 21 to enter the recess 19 in the slide 2 thereby coupling the point operating slide 1 and the slide 2 together.

Simultaneously the end of the projection 23 is raised out of the recess 24 in the locking element 26 so as to free the point operating slide 1 for movement. The final movement of the projection 23 to its upper position causes the contact 27 to engage with the contacts 28 and thereby supply energizing current to the electromagnet 6 with the result that the locking bolt 18 being lifted out of engagement with the recess 16, the slide 2 under the action of the compressed spring 3 is moved rapidly and positively towards the right carrying with it the point operating slide 1 which is coupled to the slide 2 by the bolt 21 as already explained.

It will be observed that the electromagnet 22 being mounted upon the point operating slide 1 is moved towards the right as the slide 1 moves and as soon as the slide 1 has

moved to a position corresponding to the desired setting of the points the signalman will open contact 32 to de-energize electromagnet 22. This will permit the projection 23 to enter the other recess 25 in the stationary locking element 26 so as to lock the points in their new position, the locking bolt 21 being simultaneously disengaged from the aperture 19 in the slide 2 so that the point operating slide 1 is uncoupled from the slide 2.

The reversal of slide 1 will reverse the switch device 29, and current will then flow from battery 14, through switch device 29, wire 35, contact 15^d—15^b—15^d, motor 13, and wire 34 to battery 14. This will cause motor 13 to rotate in the opposite direction, thereby moving frame 9 to the left, and this will compress spring 3 between abutment 4 and projection 8. When the spring is fully compressed, the motor circuit will be opened at switch device 15, and the apparatus will be ready for the return of the switch points when contact 32 is closed to energize electromagnet 22.

It will thus be appreciated that the energy for operating the points is derived from the compression of the spring 3, this compression being gradually effected by the operation of the motor 13 during the periods of time between the successive operations of the points, the energy thereby stored in the spring 3 serving to effect the rapid and positive movement of the points from one position to another without necessitating a sudden relatively heavy load upon the operating motor 13.

Arrangements of any suitable type may also be provided for effecting an indication at the point of control of the movement of the points to their respective positions and arrangements may also be provided for causing the points to be returned to one or other of their extreme positions in the event of their movement being obstructed from any cause during the setting operation.

The invention is evidently not limited to any particular construction or arrangement of mechanism which may be varied in order to meet particular conditions without exceeding the scope of the invention.

Having now particularly described and ascertained the nature of my said invention and in what manner the same is to be performed, I declare that what I claim is:

1. In combination, a switch actuating member, a slide bar having abutments, a spring located between said abutments, means for compressing said spring against one abutment or the other, means for locking said slide bar, and means for simultaneously coupling said slide bar with said actuating member and unlocking the slide bar to allow said spring to operate the actuating member.

2. In combination, a slide bar having abutments, a spring located between said abut-

ments, means for compressing the spring against one abutment or the other, means for locking and releasing said slide bar, and a switch actuating member controlled by said slide bar.

3. In combination, a switch actuating member, means including a spring for moving said member in opposite directions, a motor for storing energy in said spring, and
10 means responsive to movement of said member by the spring for operating said motor to store energy in the spring for the return movement of the member.

4. In combination, a switch actuating member, means including a spring for moving said member in opposite directions, a motor for storing energy in said spring between movements of said member, and means for controlling said motor by said member.

20 5. In combination, a switch actuating member, means including a spring for moving said member in opposite directions, a frame for storing energy in said spring, a motor for operating said frame, means responsive to an operation of said member for energizing said motor in such direction as to store energy in the spring for operation of the member in the other direction, and means controlled by said frame for stopping
25 said motor after the storing of energy in the spring is completed.

30 6. In combination, a switch actuating member, means including a spring for moving said member in opposite directions, a motor for storing energy in said spring between movements of said member, and means for locking said member during the storing of energy in the spring.

In testimony whereof I affix my signature.

40 DAVID GORDON DOWNES.
